UNITED STATES PATENT OFFICE.

GUSTAVE A. PEPLE, JR., OF LYNCHBURG, VIRGINIA.

CUT-OFF ATTACHMENT FOR CIGARETTE MACHINES.

Application filed August 28, 1924. Serial No. 734,708.

To all whom it may concern:

Be it known that I, GUSTAVE A. PEPLE, Jr., a citizen of the United States, residing at Lynchburg, in the county of Campbell and State of Virginia, have invented a new and useful Cut-Off Attachment for Cigarette Machines, of which the following is a specification.

This invention relates to an attachment
10 for cutting off uniform lengths from a cigarette
rod delivered from a cigarette machine of the ordinary type, one of the ob-
jects of the invention being to provide a cut-
off mechanism which will operate continu-
15 ously, cutting the rod into cigarettes and de-
livering them into a suitable container, the
cuts being clean and accurate.

A further object is to provide a novel means for conveying the cigarette rod to the cut-off mechanism and subsequently delivering the cigarettes to a container.

A further object is to provide cutting mechanism utilizing a series of cutting disks all of which rotate continuously about axes parallel with the longitudinal center of the cigarette rod, the disks being maintained in proper position relative to the rod at all times during their movement to or from the cutting positions.

30. Another object is to provide an attachment of this character which is simple and compact in construction, will not readily get out of order, and will operate efficiently at all times.

35 With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

45 In the accompanying drawings the preferred form of the invention has been shown.

In said drawings—

50 Figure 1 is a plan view of the attachment, a portion of the housing being removed and a part of the structure being shown in section.

Fig. 2 is an end elevation of the attachment, parts being broken away.

Fig. 3 is a front elevation of the attachment, a portion of the cigarette machine being shown by broken lines.

Fig. 4 is an enlarged vertical transverse section through a portion of the carrier of the cut-off.

Fig. 5 is an elevation of a portion of the 60 gearing.

Fig. 6 is a view partly in section and partly in elevation showing a portion of the mechanism for driving one of the cut-offs.

Fig. 7 is an enlarged elevation of a modification of the cigarette carrier or ledger. 65

Fig. 8 is a perspective view of one of the links of the carrier shown in Fig. 7.

Fig. 9 is a perspective view of one of the conveyor or ledger links shown in Fig. 3. 70

Fig. 10 is a longitudinal section therethrough.

Fig. 11 is a section through the housing shown in Fig. 6, the adjacent mechanism being in elevation.

Referring to the figures by characters of reference 1 designates the housing of the at-

tachment in which is journaled a transverse shaft 2 having a worm gear 3 adapted to be driven by a worm 4 carried by a shaft 5 extending from the cigarette machine which has been shown generally at M. Shaft 2 is provided with a gear 6 which, as shown particularly in Fig. 3, meshes with intermediate gears 7, one of which has a sprocket 8 connected thereto so as to rotate therewith. The gears 7 mesh with smaller gears 9, each of which is secured to a shaft 10 extending transversely in the housing 1 and provided at one end with a sprocket 11 of novel construction. This sprocket is provided with spaced annular flanges 12 intersected at regular intervals by recesses 13 so that the flanges thus produce elongated teeth or projections. The flanges are spaced apart sufficient distances to receive between them the links of a carrier or ledger shown in detail in Figs. 3 and 9. Each link has a longitudinal channel 14 in its outer face and a pair of ears 15 extending from one end. 100

The ears on each link are adapted to fit in recesses 16 in the next adjoining link and are connected to said link by pins 17 on which are mounted small rollers 18. As shown in Fig. 3 the links are so proportioned that the rollers 18 will project into the recesses 13 while the links extend between the elongated teeth or projections 12 formed by the flanges. These links make up an endless carrier or ledger engaging both sprockets 11 and located between the upper portions of the sprockets is a suitable table or other sup-

port 19 on which the rollers may travel while passing from one sprocket to another. Thus that portion of the upper part of the conveyor between the sprockets will be 5 properly supported during the cutting operation hereinafter described.

Although it is preferred to provide sprockets and links such as described it is to be understood that other forms may be 10 used. For example, and as shown in Figs. 7 and 8 the sprockets can be provided with V-shaped teeth 20 instead of elongated teeth or projections such as shown in Fig. 3. Where sprockets of this shape are used the 15 links are preferably constructed as shown in Figs. 7 and 8. Each link includes a block 21 having a longitudinal channel 22 in its outer face while ears 23 extend from one end. These ears are adapted to extend into 20 recesses 24 formed in the next adjoining link to which they are connected by a pin 25 having rollers 26 thereon. The blocks are arranged in pairs, the blocks or links of each pair normally abutting at one end as 25 shown at 27 while one end of one block or link of each pair is beveled as at 28. Thus an angular recess 29 is provided between adjoining pairs of links. The teeth 20 are 30 adapted to project between the rollers 26 and the distance between the recesses 29 is equal to the length of the cigarettes to be cut. In the form shown in Figs. 7 and 8 the links are approximately one-half the 35 length of each link shown in Figs. 3 and 9. 35 The upper portion of the conveyor or ledger made up of the links is disposed in line with the delivery outlet of the cigarette machine so that when a cigarette rod R is delivered 40 from the machine it will be directed onto and be supported by the ledger, or conveyor. The mechanism is so timed that this 45 conveyor will travel at the same speed as the ejected cigarette rod, the proper timing being affected by the mechanism employed for transmitting motion to the conveyor or ledger from the cigarette machine.

The sprocket 8 drives an endless chain 30 which serves to transmit motion to small sprockets 31 secured to transverse shafts 32. 50 Each of these shafts is provided with a wheel 33 having a grooved periphery. The two wheels are located directly above the centers of the sprockets 11 and are adapted to engage the cigarette rod as shown in 55 Fig. 3 and facilitate the movement thereof with the conveyor or ledger. The sprockets and chain as well as the gearing for driving the same are so timed that the peripheral speed of the wheels 33 will be the same as the speed of movement of the conveyor or 60 ledger cooperating with the wheels.

The gear 6 meshes with a gear 34 and this in turn drives a gear 35 secured to a shaft 36 journaled in a suitable standard 37.

65 Another gear 38 is secured to the other end

of this shaft 36. Gear 35 meshes with a gear 39 secured to a shaft 40 and this shaft extends through a fixed sleeve 41 secured in the standard. A gear 42 is secured to and rotates with the shaft 40. Mounted for rotation on the sleeve is a hub 43 extending from a disk 44 and to this hub is secured a gear 45 which meshes with the gear 38. A head 46 is secured to the sleeve 41 so as to be held against rotation and on this head is 70 journaled a gear 47 which meshes with the gear 42 and serves to transmit motion to a gear 48. This last named gear is secured to the hub 49 of a disk 50, said hub being journaled on a fixed shaft 51 extending laterally 75 from the head 46. Thus it will be seen that the axis of rotation of disk 44 is out of alignment with the axis of rotation of disk 50 as will be plainly apparent by referring to Fig. 1. The axes of these two disks are fixed, however, and by providing the gears described the two disks can be rotated clockwise at the same speed. Pivotedly connected to the disk 44 at regular intervals are crank 80 arms 52. These crank arms are parallel and each of them is secured fixedly to a stem 53 extending from one end of a shaft 54. The shafts are parallel and are mounted in the marginal portion of disk 50. These shafts 85 extend laterally from disk 50 and as the two disks 44 and 50 rotate at the same speed the crank arms 52 attached to the shafts will tend to hold the shafts against rotation while disk 50 revolves. In other words the shafts 54 are free to move with disk 50 about shaft 51 but will not rotate about their own axes. 90

Each shaft 54 is provided at its outer end with an integral housing 55 in which is journaled a shaft 56 to the outer end of which is secured a cutting disk 57. This shaft has a pinion 58 meshing with a pinion 59 secured to a tubular shaft 60 journaled on shaft 54 and provided with a gear 61. The gears 61 of the several tubular shafts engage a stationary ring gear 62 fixedly mounted on the fixed shaft 51 and in the housing 63 which normally conceals disks 44 and 50 and the parts associated therewith. All of the shafts 56 lie in parallel planes and are parallel with the line of movement of the cigarette rod R. Consequently all of the cutting disks 57 are constantly parallel and perpendicular to the line of movement of the cigarette rod. These relative positions remain unchanged 110 during the movement of the shafts 54, 60 and 56 about the axis of the disk 50.

In the operation of the machine the main shaft 5 will drive the gears as hereinbefore 115 pointed out so that the endless conveyor or ledger made up of the links 14 or 21 will carry the ejected cigarette rod over the table 19 and beneath the cutting disks 57. This movement of the rod will be facilitated by 120 the grooved wheels 33. As the disks 44

and 50 rotate at the same speed but about different centers the constantly parallel cranks 52 will maintain the shafts 56 horizontal so that the cutting disks 57 will be moved downwardly successively into engagement with the cigarette rod. During this rotation of disk 50 the gears 61 will travel along gear 62 so as to rotate shafts 60 and drive the cutting disks at a high speed. Consequently as each disk descends into contact with the cigarette rod it will sever it, the parts being so timed that the disk will enter the space between two of the links of the conveyor or ledger. The severed cigarettes will be carried away from the cutters by the conveyor or ledger and will ultimately be directed into a hopper 64 and thence to a receiver. It will be noted that the groove in the rear end of each ledger link is so shaped that as the link starts to move downwardly about its supporting sprocket the distance between the bottom of the grooved wheel 33 above said sprocket and the bottom of the groove in the link of the ledger will remain the same. Thus the cigarette will not be pinched but will be slid straight out onto the trough 65 leading to the hopper 64.

As before pointed out each link or each pair of links of the conveyor or ledger has a perpendicular face or end indicated, for example, at 66 in Fig. 9 and 67 in Fig. 8. The parts are so timed that as each cutting disk descends to sever the cigarette rod it will cooperate with or work against one of these vertical faces to render the shearing operation more efficient.

What is claimed is:—

1. In a cut-off for cigarette machines, a continuously moving conveyor for supporting a cigarette rod, a rotatable series of cutters, means for maintaining the cutters perpendicular to the cigarette rod, means for rotating the series of cutters about a common axis to bring them successively into engagement with the supported rod, and means operated by the rotation of the cutters about said axis to revolve the cutters about individual axes.
2. In a cut-off for cigarette machines, a conveyor for supporting a cigarette rod mounted for continuous right line movement, a cut-off disk, means for moving the disk continuously and at uniform speed in a circle in a plane parallel with the direction of movement of the conveyor, means for holding the disk perpendicular to the cigarette rod during its movement in a circle, and means for rotating the disk about its individual axis during the circular movement thereof.
3. In a cut-off for cigarette machines, a continuously moving conveyor for supporting a cigarette rod, a plurality of cut-off disks, means for moving the disks continuously in a circle about a common center, means for maintaining the disks perpendicular to the cigarette rod during their movement about said center, and means operated by the circular movement of the disk for rotating the same about their individual axes.
4. In a cut-off for cigarette machines the combination with a conveyor for supporting a cigarette rod, said conveyor including links having perpendicular ends, of a cut-off disk mounted for rotation in a circle, means for maintaining the disk perpendicular to the conveyor during such rotation, and means for rotating the disk about its individual axis during the rotation thereof, said disk cooperating with one of the perpendicular ends of the conveyor links to shear off the cigarette rod.
5. In a cut-off for cigarette machines the combination with a conveyor for supporting a cigarette rod, said conveyor having links with perpendicular ends, of a plurality of cut-off disks mounted for movement in a circle about a common center, means for maintaining the disks perpendicular to the conveyor during their movement in a circle, and means operated by the movement of the disks in a circle for rotating them about individual axes and bringing them successively into cooperation with the perpendicular ends of the links to shear off material in the paths thereof.
6. In a cut-off for cigarette machines the combination with disks mounted for simultaneous rotation about parallel non-aligning axes, of arms connecting the disks and journaled thereon, means for rotating the disks simultaneously to maintain the arms parallel, cut-off disks, connections between the cut-off disks and the arms for maintaining said cut-off disks perpendicular during the rotation of the first named disks.
7. In a cut-off for cigarette machines the combination with disks mounted for simultaneous rotation about parallel non-aligning axes, of arms connecting the disks and journaled thereon, means for rotating the disks simultaneously to maintain the arms parallel, cut-off disks, connections between the cut-off disks and the arms for maintaining said cut-off disks perpendicular during the rotation of the first named disks, a shaft operatively connected to each cut-off disk, a gear thereon, and a stationary gear constantly in mesh with the gears of the cut-off disks for rotating them during the movement of the disks about a common center.
8. In a cut-off for cigarette machines the combination of a conveyor including pivotally connected ledger links, each link having a groove, and wheels overhanging the conveyor for holding the cigarette rod in the grooves, the bottom of one end of the groove in each link being rounded, whereby a cigarette passing between a grooved wheel and a link

at a point where the link changes its direction of movement, will continue on in a straight line.

9. In a cut-off for cigarette machines the combination with a conveyor including pivotally connected links each having a cigarette holding groove, of grooved wheels extending into the grooves of the links and

straddling cigarettes supported by the links, and means for driving the wheels and conveyor so that their cigarette engaging faces will travel at the same speed.

In testimony that I claim the foregoing as my own, I have hereto affixed my signature.

GUSTAVE A. PEPLE, JR.
